UNITED STATES PATENT OFFICE.

MILES L. DAVIS, OF LANCASTER, PENNSYLVANIA.

GARBAGE-CREMATORIY.

No. 906,115.

Specification of Letters Patent.

Patented Dec. 8, 1908.

Application filed February 10, 1908. Serial No. 415,028.

To all whom it may concern:

Be it known that I, MILES L. DAVIS, a citizen of the United States, residing at Lancaster, in the county of Lancaster and State of Pennsylvania, have invented certain new and useful Improvements in Garbage-Crematories, of which the following is a specification, reference being had therein to the accompanying drawing.

My invention relates to a furnace for the consuming of garbage and other refuse matter, and is an improvement over Patent No. 432,035, issued to me on Oct. 27, 1891; for furnace for burning garbage, and my present invention is designed to quickly and economically consume the garbage, without liberating gases or odors, and by the use of the garbage itself largely as fuel.

Another object of the invention is to provide a furnace of the class described in which the walls are supplied with air spaces, or chambers and passages for the purpose of keeping the walls cool and prolonging their life, and further to provide said furnace with a system of stays and braces to strengthen the walls and arches, as furnaces of this class are exposed to excessive heat.

I also provide a novel method of operating the charging door or cover, and an inclined garbage grate, evaporating pan and approved means of communicating with, and flushing out said pan.

The uses and arrangement of the various chambers are substantially the same as in my former patent, and I will, therefore, more particularly point out the features of my present invention.

I have here shown and described my invention in the form of a single furnace, but it is understood that they may be constructed in a series, and that slight changes may be made in the construction and the selection of material without departing in any way from the spirit of the invention.

Like reference figures indicate corresponding parts in all the figures of the drawing.

In the drawings:—Figure 1, is a side elevation of my furnace with the side platform removed, and showing the boundaries of the side air chamber. Fig. 2, is a front elevation with the side platform removed and showing the air chamber in dotted outline. Fig. 3, is a section on the line $z-z$, of Fig. 2, showing the arrangement of the firing chambers, grates, etc. with the air chambers in dotted outline and the smokestack cut away. Fig.

4, is a top plan view of the furnace with the side platform broken away. Fig. 5, is a section on the line $z-z$, of Fig. 3. Fig. 6, is a sectional plan view on the line $y-y$, of Fig. 1, 60 showing the air chamber. Fig. 7, is a partial sectional view in detail of the charging door cap and means for operating the same.

My device consists of a furnace constructed of brick or other suitable material, properly lined with fire bricks, and divided into three chambers, consisting of a primary or main fire-chamber 1, having set in its front wall a front-plate or plates 2, containing the fire-doors 3, and the ash-pit doors 4, all 65 hinged and latched in the usual way and communicating through the front wall 5, with said fire-chamber 1, and the ash-pit 6, which is divided from said firing chamber by the grate 7.

In the central part of the device is situated the garbage receiving and drying chamber 8, which extends from some distance above down to about the level of the primary fire-chamber 1, and from which it is separated by the 80 bridge-wall 9. The top or upper portion of said chamber 8, has side walls terminating in an arch and pierced by the charging opening 10, and surmounted by the collar 11, upon which rests the cap or cover 12, 85 which is adapted to close tightly, confining all fumes and vapors within. The front wall of said chamber 8, above the platform 13, is provided with the stoking door 14, formed with the inwardly inclined sill 15, 90 said opening designed for the purpose of inserting hooks or rakes for drawing the garbage forward upon the firing grate.

Near the rear wall 16, of the chamber 8, is secured the grate support 17, with its ends 95 embedded in the side walls of said chamber; and near the wall 9, is secured the grate support 18, on a lower level with its ends embedded in the side walls, and upon said supports rests the garbage grate bars 19, which 100 cover the horizontal area of said chamber 8. Underneath said grate 19, and resting upon a projection 20, of the bridge-wall 9, and rear wall 16, is placed the evaporating tank 21, extending over this portion of the chamber 8, said tank having a neck or spout 22, extending through the side wall of said chamber 8, and being capped or closed by the plate 23, secured thereto and forming a water-tight joint therewith. Resting upon 110 the upper sides of said tank 21, is a water pipe 24, which extends from a point over

the side of said tank opposite the spout 22, to the rear and along the back of said tank, through a chamber 25, in the side wall of said chamber 8, where a cut off 26, is placed, 5 to the source of supply.

Behind the garbage chamber 8, and well toward the top thereof, is located the smoke-burning or secondary fire-chamber 27, having a fire door 28, and an ash door 29. This 10 chamber is provided with a fire grate 30, resting on lugs or brackets 31, projecting from the two side walls, and its ash-pit 32, opens throughout its entire extent into the air chamber hereinafter more fully described; while near its top, through the rear wall, is an opening 33, communicating with the smoke-flue 34, which is placed at the rear of all and connects with the main stack. Upon the outer surface of the side walls of 20 said chamber 8, at a point opposite the arch of said chamber are placed the retaining plates 35, and upon the outer surface of the side walls of the firing-chamber 1, near the top thereof, and opposite the arch of said 25 chamber, are placed the retaining plates 36.

Upon the outer corners of the outer walls of said furnace are secured the angle irons 37, which are provided with the lugs 38, through which are passed and secured the ends of the 30 buck-stays 39, which in connection with the angle irons are designed to firmly brace and secure the side and end walls of the furnace; and said walls are further strengthened and secured by the vertical braces 40, which 35 have their lower ends secured in the ground and their upper ends secured by transverse stay-bolts extending from side to side of said furnace. Said braces also bear against and securely retain in place the retaining plates 40 35, and 36.

For cooling and preserving the outer walls of said furnace from cracking I provide an air chamber 41, contained within the walls of said furnace and which extends from the 45 level of the firing-grate to the level of the ash-pit of the smoke burning-grate 30, and which communicates with the air chamber 42, which is formed between the front wall 5, and the front plate 2, and communicating 50 at the rear with the air-chamber 43, which connects with the ash-pit 32. The outer sides of the furnace are pierced at intervals upon the lower level of said air-chamber by the orifices 44, which connect said chamber 55 with the outer air, and when taken in connection with the opening into the ash-pit 32, forms and provides a draft or circulation of air between the inner and outer walls of said furnace where the greatest heat is 60 maintained.

The top of the chamber 8, is provided with a flooring 45, and at a suitable distance above said flooring is secured the track 46, to any suitable support, such as the roof, rafters, 65 etc. Upon said track 46, is slidably mount-

ed the hanger 47, which is provided with the swivel 48, to which is pivoted the lever 49, nearer one of its ends than the other; while to its shorter end is secured one end of the rod 50; while to the other end of said rod 50, 70 is fastened the cap or cover 12, and to the longer end of the lever 49, is secured the rod 51, which terminates in the hand ring 52.

The operation of my device as a whole is as follows:—The cover 12, having been raised 75 clear of the charging opening or doorway by the lever 49, and the hand-rod 51, and carried by the hanger and track out of the way, the garbage is dumped into the chamber 8, the cover 12, returned to its place, and a fire built 80 in the smoke-burning chamber 27. A fire is now started in the main firing-chamber 1, the smoke from same passing through the garbage chamber 8, and together with the vapor from said garbage is consumed by the 85 fire in the chamber 27. When the fires are well under way and the garbage has been drained into the evaporating pan and partly dried by the heat, the operator rakes through the stoke-door 14, the garbage upon the fire 90 in the chamber 1, thus using said garbage as fuel and consuming it, while the liquid drained from said garbage is retained in the pan 21, and evaporated by the heat in said furnace. The fire from the main firing-chamber 1, on passing through the garbage chamber 8, will convey all gases, etc. to the chamber 27, where they will be consumed, thus destroying all odors, vapors, etc. After 95 the chambers have been thoroughly heated 100 the fire in the chamber 27, can be let out as the heat of the other chambers will consume all gases before they enter the smoke flue. To clean out the evaporating pan the plate 105 23, is removed, the water turned on by the cut off in the chamber 25, and said pan flushed out.

Having thus described my invention what I claim as new and desire to secure by Letters Patent is:—

1. In a garbage crematory of the class described, comprising firing, garbage and smoke-consuming chambers, the front, end and side walls of said crematory provided with air spaces, ducts piercing the outer walls and communicating with said air spaces, said air spaces communicating at the rear of said crematory with the smoke flue and at the front of said crematory with the ash-pit of the firing chamber.

2. In a garbage crematory of the class described, comprising a firing chamber, a garbage drying chamber communicating therewith and situated in the rear of and extending into a higher plane than said 115 firing chamber, a smoke-consuming chamber situated in the rear of and in a higher plane than said garbage chamber and communicating therewith and with the main flue of said crematory, angle irons formed with 120 125 130

lugs embracing the corners of the outer walls
of said crematory, plates set into the side
walls of said crematory opposite the arches
of said chambers, buck-stays having their
5 ends secured to said lugs and placed with
their sides in contact with said plates and
the sides of said walls, for the purpose of
binding said walls together and retaining
said plates, upright braces having their

lower ends embedded in the ground and their 10
upper ends secured to the top of said walls.
In testimony whereof I affix my signature
in presence of two witnesses.

MILES L. DAVIS.
